[57] CLAIM

The ornamental design for an image display housing, as shown and described.

DESCRIPTION

FIG. 1 is a perspective view of an image display housing of this invention;

FIG. 2 is a front elevational view thereof;

FIG. 3 is a left side elevational view thereof, the right side being a mirror image thereof;

FIG. 4 is a top plan view thereof; and

FIG. 5 is a rear elevational view thereof.

FIG. 6 is a front elevational view of an alternate embodiment of this invention;

FIG. 7 is a left side elevational view of the alternate embodiment of FIG. 6, the right side being a mirror image thereof;

FIG. 8 is a rear elevational view of an alternate embodiment thereof; and,

FIG. 9 is a top plan view of an alternate embodiment the bottoms of both embodiments are unornamented.
